UNITED STATES PATENT OFFICE

2,207,269

NONSLIP SHAVING IMPLEMENT

Henry T. Schiff, Chicago, Ill.

Application November 16, 1938, Serial No. 240,665

1 Claim. (Cl. 30—90)

My invention relates to a shaving implement which has a nonslip handle or gripping portion.

Among the objects of my invention is to provide an electric dry shaver with means to prevent it from slipping out of the hand of the user, particularly during the shaving operation, said means taking the form of a handle having a nonslip portion or member at the gripping position, and such other objects, advantages and capabilities as will 10 later more fully appear and which are inherently possessed by my invention.

While I have shown in the accompanying drawing a preferred embodiment of my invention, yet I wish it understood that the same is susceptible of modification and change without departing from the spirit of my invention.

Referring to the drawing Fig. 1 is a perspective view of my shaving implement with a nonslip member in position ready for use; Fig. 2 is a 20 detail perspective view of the preferred form of my detachable nonslip member; Fig. 3 is a perspective view broken away in part to show the cooperation between the ribs on the handle and the ribs on the ring, and Fig. 4 is a perspective 25 view of a slightly different embodiment of my nonslip shaving implement.

Referring more particularly to the preferred embodiment selected to illustrate my invention, it comprises a shaving implement 10 having a 30 handle or body portion 11 ordinarily constructed of smooth plastic material such as Bakelite. A substantially ring shaped member 12 made of rubber or desirable nonslip composition is positioned laterally around the handle 11 and is formed so as to fit thereagainst by friction grip. The member 12 has elastic properties so that it 35 may be stretched for position and removal.

The outer surface of the nonslip member 12 has raised portions 18 to provide a nonslip surface for the hand of the user.

A slightly different embodiment is to provide the nonslip member with inwardly extending portions such as spaced longitudinally extending 45 ribs 13. These will rest in longitudinal grooves 14 between longitudinal ribs 15 on the outer surface of the handle 11. These members 13 and

14 will tend to prevent any lateral movement of the member 12 with respect to the handle 11.

Another embodiment is to provide the handle 11 with a recess 16 in which is positioned and permanently attached by adhesive or any suitable means a nonslip portion 17 of nonslip material. The recess may be annular and extend around said handle, or I may provide recesses on the front and back of the handle to receive nonslip portions.

In use my shaving implement is more efficient than those having a smooth outer surface on the handle. My nonslip shaving implement prevents the hand of the user from slipping during the shaving operation. The user is more certain, and with added confidence and no slipping of the shaving implement may shave better and more quickly. Whenever the user puts the shaving implement down on a table or the like with the motor running the raised portions 18 will prevent 20 the implement from sliding off the table.

Having thus described my invention, I claim:

In combination with an electric dry shaver having a body portion adapted to be held by the hand of the user during the shaving operation, 25 said body portion being of smooth plastic material and having a plurality of spaced longitudinal ribs and grooves, a substantially ring shaped member of nonslip material removably and laterally positioned around that portion of the 30 body portion of the shaving implement gripped by the user while shaving, said substantially ring shaped member having elastic properties so that the same may fit against the body portion by friction grip to prevent accidental displacement 35 and also be stretched for position and removal, a plurality of spaced longitudinally extending ribs on the inner portion of said substantially ring shaped member, said ribs lying within the grooves on the outer surface of the body member to prevent any lateral movement of the substantially 40 ring shaped member with respect to the body portion, and raised portions on the exterior of said substantially ring shaped member to further aid in preventing the hand of the user from 45 slipping during the shaving operation.

HENRY T. SCHIFF.
